[57] CLAIM

The design for an automated apparatus for cutting thick plate rolled stock, substantially as shown and described herein.

DESCRIPTION

FIG. 1 is a perspective view of an automated apparatus for cutting thick-plate rolled stock, showing our new design;

FIG. 2 is a top view thereof;

FIG. 3 is a side view, taken from the right side of FIG. 1;

FIG. 4 is a side view, taken from the left of FIG. 1;

FIG. 5 is a front view thereof; and

FIG. 6 is a rear view thereof.

FIG. 1

FIG. 2

FIG. 3

FIG. 4

FIG. 5

FIG. 6
